UNITED STATES PATENT OFFICE.

ALBERT GEORG KOECHLIN, OF STEINEN, GERMANY, ASSIGNOR TO DRAPER COMPANY,
OF HOPEDALE, MASSACHUSETTS, A CORPORATION OF MAINE.

LOOM-STOPPING MECHANISM.

1,082,086.

Specification of Letters Patent. Patented Dec. 23, 1913.

Application filed July 23, 1910. Serial No. 573,528.

To all whom it may concern:

Be it known that I, ALBERT GEORG KOECHLIN, a citizen of the Republic of Switzerland, residing at Steinen, Grand Duchy of Baden, Germany, have invented certain new and useful Improvements in Loom-Stopping Mechanism, of which the following is a specification.

In automatic weft-replenishing looms, it sometimes occurs that the weft is replenished too frequently owing to the breakage of the thread, the imperfect action of the weft replenishing mechanism, and otherwise, so that the reserve supply of weft is rapidly exhausted entailing additional labor, and cloth having undue defects or blemishes is woven. It is important, therefore, that the loom should be automatically stopped in the event of such too frequent actions of the weft replenishing mechanism in order that the cause may be discovered and remedied and the proper character of cloth may be woven.

The present invention, therefore, has for its object the automatic stopping of the loom in the event that the replenishment occurs with too great frequency.

The present improved stopping mechanism is illustrated in the accompanying drawings, wherein—

Figure 1, is a diagram illustrating the improved mechanism. Fig. 2, is a horizontal cross-section of the shipper lever showing the catch or notch for holding it in its position while the loom is running. Fig. 3, is a side elevation of the stop controlling mechanism. Fig. 4, is a front elevation of the stop controlling mechanism.

The framework of the loom is indicated at **a** and on a part of the frame is located a bracket **b** which carries the stop controlling mechanism. This mechanism comprises a controller **f** which is fixed to a ratchet wheel **c** on a shaft **b¹**. This controller **f** is initially held against a stop **f¹** by means of a coiled spring **x**, shown best in Fig. 3. This controller **f** is advanced step-by-step by actuating means (hereinafter described) toward an electric contact **g** and reaches said contact after a predetermined number of steps have been made. When the controller **f** touches the contact **g** the loom stopping devices are put into action, the shipper lever thereof being tripped through appropriate connect-

ing means which, as illustrated, are electrical in character.

The bracket **b**, which is of metal, is insulated from the framework of the loom and is in metallic contact with controller **f**. This bracket, and hence the controller, are connected with one pole of an electric source **k** by means of the circuit wire **l**. The contact **g** is insulated from the bracket **b** and from it leads a circuit wire **h**. This wire **h** and a circuit wire **h¹** extending from the opposite pole of the electric source **k** extend to electric terminals which cooperate with two contact springs **r**, **r**, carried by the shipper lever. These spring contacts connect with opposite poles of an electric magnet **i** also carried by the shipper lever. The electric circuit is normally open, but when it is closed by the controller **f** touching the contact **g** then the electromagnet **i** is energized, thereby lifting its pivoted armature **m** into the path of a sliding bunter **n** pivotally connected to the upper end of a crank arm **o** on the lay rock shaft **o¹**. Accordingly, at the next forward beat of the lay, the bunter **n** encounters the armature **m** and pushes the shipper lever **p** out of its holding notch **q** (Fig. 2) and the loom is stopped in a usual manner by the customary connections between the shipper lever and the direct stopping mechanism of the loom which is not shown because of well-known character.

The step-by-step advance of the controller **f** is governed by an actuator **e**, which is moved each time that the weft is replenished. The actuator **e** consists of a pawl **90** which is pivoted upon a lever **d²** which is itself pivoted upon the ratchet shaft **b¹**. The actuator **e** is pressed toward the ratchet wheel **c** by means of a spring **z**. The upper end of the lever **d²** is connected by a link **95** **d²** with the lower end of a crank arm **d¹**. The upper end of this crank arm is fastened upon a rock shaft **d**. This rock shaft is a shaft which is rocked each time that the weft is automatically replenished in unison with a rock shaft such as shown at 14, in United States Letters Patent No. 971,541, granted October 4, 1910, to myself or such as the rock shaft **d¹** of United States Letters Patent of Northrop, No. 529,940, November 27, 1894. The rock shaft **d** shown in the accompanying drawings can be connected with the customary rock shaft, such

as shown in the patents just mentioned, by any suitable intervening connections, such for example, as the cranks 3 and 6 and the link 4 which connect the rock shafts 100 and 5 71 shown in the United States Letters Patent of Entwistle, No. 841,492, January 15, 1907, for mechanism for automatically changing shuttles in looms. The actuator *e* and its connected parts, are illustrated in 10 their normal idle position by full lines in Fig. 1 and at that time the actuator *e* is held out of contact with the ratchet *c* by means of the pawl lifter *y*. This pawl lifter *y* may be a pin, rigidly secured to the 15 bracket *b* as shown in Fig. 1, or it may be the free end of an adjusting screw *c'*, as shown in Fig. 4, this adjustment regulating the number of teeth on the ratchet which the actuator rides over on its return stroke, 20 thereby determining the extent of the advance steps of the controller *f* and hence the number of steps which the controller takes in moving from its initial position to its position where it touches the electric contact *g*. When the rock shaft *d* oscillates 25 (which occurs when the weft is replenished in the usual well-known manner) it is moved to its dotted line position shown in Fig. 1, thereby bringing the actuator *e* into 30 contact with the ratchet *c*, thereby advancing the controller *f* one step toward the electric contact *g*. The controller *f* is maintained at each of its steps in advance by means of a detent *w* (see Fig. 4) which is 35 pressed against the ratchet wheel *c* by means of the spring *z*. If the predetermined but adjustable number of these steps occurs, then the controller *f* comes into touch with the contact *g* and the loom is stopped, 40 through the usual loom stopping devices of which the shipper lever is a representative part. In case, however, less than the predetermined number of advance steps of the controller occurs during the lapse of a 45 period corresponding to the running of the loom with a normally lasting supply of weft, then the controller *f* is restored to its initial position resting against the stop *f'*. This restoring mechanism for the controller comprises a lever *v* which is pivoted at *u* and 50 which is integral with the detent *w*; and a uniformly advancing releaser *t* which is carried by a moving disk *s* turning on the shaft *s'*. As shown, there are several of the 55 releasers *t*, projecting from and uniformly spaced upon the wheel *s*. This restoring mechanism is timed to reset the controller to its initial position after the lapse of a period corresponding to the running of the 60 loom with a normally lasting supply of weft. To this end the wheel *s* rotates slowly by appropriate connections with a moving part of the loom. The particular mechanism for thus rotating the disk *s* constitutes 65 no part of the present invention. It may be

any suitable reducing gearing driven by the usual crank shaft or cam shaft of the loom, such gearing being common in giving a slow motion to a take-up, as for example, in United States Letters Patent of Crompton & Fitton, No. 787,281, April 11, 1905; or for actuating a measuring mechanism such as is illustrated in United States Letters Patent to Draper and Northrop, No. 462,919, November 10, 1891, or in the Crompton and Wyman United States Letters Patent No. 600,121, March 1, 1898, but so timed that one of the releasers *t* will successively encounter the detent arm *v* at definite intervals, each of which corresponds approximately to the time a single supply of weft should normally last. When one of the releasers *t*, moving in the direction of the arrow shown in Fig. 1, encounters the detent arm *v*, the detent *w* is swung away from the ratchet *c*, thereby releasing the ratchet, whereupon the controller *f* is reset to its initial position against the stop *f'* by the spring *z*. Assume, therefore, that the character of the fabric being woven is such that there should not be four weft replenishments during the period normally required for the exhaustion of a single supply of weft. In such case, the controller *f* is so adjusted that it will step in advance four times before reaching the electric contact *g*. If it does make these four steps, then the loom is automatically stopped and the weaver or the fixer can find out the reason for the frequent change and correct it. In case, however, less than four replenishments occur during the prescribed interval, then one of the releasers *t* comes into action and restores the controller *f* to its initial position. The adjustment enables the predetermined number of advance steps of the controller necessary to bring about the stoppage of the loom to be regulated. Accordingly, the frequency of permissible weft-replenishment within a given interval can be regulated in accordance with the character of the cloth being woven. 110 During the definite period which must elapse before the restoring mechanism acts, cloth is being woven by the loom which continues its normal operations in weaving unless the prescribed number of actions of the weft-replenishing mechanism occurs during the interval. The frequency of the movements of the controller is irregular and indefinite being determined solely by the indeterminate action of the weft-replenishing mechanism. 115

I claim:—

1. A stopping mechanism for automatic weft-replenishing looms having, in combination, a shipper lever; a step-by-step moving controller; connecting means between said controller and shipper lever whereby after a predetermined but adjustable number of advance movements of the controller 120

- the shipper lever is tripped to stop the loom; an actuator for said controller which is moved each time the weft is replenished to advance said controller one step; and restoring mechanism for said controller, including a uniformly advancing releaser, timed to reset the controller to its initial position after the lapse of a period corresponding to the running of the loom with a normally lasting supply of weft.
2. A stopping mechanism for automatic weft-replenishing looms having, in combination, loom-stopping devices, a step-by-step moving controller; connecting means between said controller and said stopping devices whereby after a predetermined but adjustable number of advance movements of the controller the loom is stopped; an actuator for said controller which is moved each time the weft is replenished to advance said controller one step; and restoring mechanism for said controller, including a uniformly advancing releaser, timed to reset the controller to its initial position after the lapse of a period corresponding to the running of the loom with a normally lasting supply of weft.
3. A stopping mechanism for automatic weft-replenishing looms having, in combination, loom stopping devices; a step-by-step moving controller; connecting means between said controller and loom stopping devices whereby after a predetermined number of advance movements of the controller the loom is stopped; an actuator for said controller which is moved each time the weft is replenished to advance said controller one step; and restoring mechanism for said controller timed to reset the controller to its initial position after the lapse of a period corresponding to the running of the loom with a normally lasting supply of weft.
4. A stopping mechanism for automatic weft-replenishing looms having, in combination, loom stopping devices; a controller having step-by-step movements occurring at indeterminate intervals; connecting means between said controller and loom stopping devices whereby after a predetermined but adjustable number of advance movements of the controller the loom is stopped; an actuator for said controller which is moved each time the weft is replenished to advance said controller one step; and restoring mechanism for said controller timed to reset the controller to its initial position after the lapse of a definite period in the weaving of cloth by the loom.
5. A stopping mechanism for automatic weft-replenishing looms having, in combination, loom stopping devices; a controller having successive advance movements occurring at indeterminate intervals; connecting means between said controller and loom stopping devices whereby after a predetermined number of advance movements of the controller the loom is stopped; an actuator for said controller which is moved each time the weft is replenished to advance said controller one step; and restoring mechanism for said controller timed to reset the controller to its initial position after the lapse of a definite period in the weaving of cloth by the loom.
6. A stopping mechanism for automatic weft-replenishing looms having, in combination, loom stopping devices; an indeterminately movable controller operatively connected with said loom stopping devices whereby after a predetermined number of movements of the controller the loom is stopped; an actuator for said controller which is moved each time the weft is replenished to move said controller; and restoring mechanism for said controller timed to reset the controller after the lapse of a definite period in the weaving of cloth by the loom.

Signed by me this 7 day of July 1910.
